UNITED STATES PATENT OFFICE.

THOMAS ALLSOP, OF PHILADELPHIA, PENNSYLVANIA, ASSIGNOR TO THE PHILADELPHIA DRYING MACHINERY COMPANY, OF PHILADELPHIA, PENNSYLVANIA, A CORPORATION OF PENNSYLVANIA.

DYEING MACHINE

Application filed August 14, 1922. Serial No. 581,567.

To all whom it may concern:

Be it known that I, THOMAS ALLSOP, a citizen of the United States, residing at Philadelphia, county of Philadelphia, and

5 State of Pennsylvania, have invented certain new and useful Improvements in Dyeing Machines, of which the following is a specification, reference being had to the accompanying drawings.

10 This invention relates to cylindrical article holders for dyeing, bleaching and washing machinery, and an object of the invention is to generally improve the construction of this element and more particularly to provide an improved design 15 wherein the parts of the cylinder or article carrier are assembled with a view to avoiding parts projecting into the cylinder, such as rivet heads, bolts, flanges, etc., so that 20 delicate fabrics and articles may not be snagged or otherwise injured when tumbled during rotation of the cylinder.

Another object of the invention is to provide a cylinder of the character described 25 which is polygonal in cross section, providing a series of flat sides upon its inner surface to ensure proper tumbling of the articles without entangling the same and having radial partitions defining pockets 30 in which the articles are separately contained.

In addition to the foregoing this invention comprehends improvements in the details of construction and arrangement of 35 the correlated parts to be hereinafter set forth and particularly pointed out in the appended claims.

In the accompanying drawings, Fig. I is a view in transverse section taken through 40 a drum of my improved construction illustrating it in position within a vat.

Fig. II is a view in longitudinal section.

Fig. III is a view of the drum per se in end elevation.

45 Fig. IV is a view in elevation of a fragment of the cylinder showing a door construction; and

Fig. V is a view in transverse section taken through the door, showing in detail 50 an improved locking mechanism.

Fig. VI is a detail view of the locking mechanism in plan.

Fig. VII is a detail view in transverse

section taken on the line VII—VII of Fig. VI; and

Fig. VIII is a view of the locking mechanism in perspective.

With reference to the drawings, 10 indicates a vat of conventional form having a door 11 for entry of articles into the cylinder or drum indicated generally at 12. The latter comprises a pair of end members, each a duplicate of the other in construction and consisting of four segmental sections 13 arranged in circumferential relation as 15 shown in Fig. III. Each section is formed with diverging radial sides 14, connected at their adjacent ends by means of the straight side member 15, and at their remote ends by means of the perimetrical member 16, which is bent at several places to provide flat attaching portions 17, the latter defining the sides of a regular polygon when the segmental sections are assembled. The entire perimetrical portion of each segment is preferably angular in cross section 20 defining the inner flanges 18 and outer flanges 19, the latter being apertured at numerous places for the reception of bolts 20 to secure the segments together. The assembly of the segments results in the definition of a quadrangular central opening within which is fitted a journal member 21 and comprising four substantially triangular sections 22 of duplicate construction, each consisting of a web portion 23, a lateral base flange 24 for abutment against a flange 19 of an adjacent segment 13, converging side flanges 25 for mutual 25 abutment and an arcuate recess 26, the latter defining a central opening for the reception of a tubular shaft or axle 27. The edges of the recesses 26 and adjacent portions of the flanges 25 are reinforced by the provision of additional metal, as indicated at 28 and 29 respectively. The thickened portions 29 are apertured for the reception of bolts 30 which serve to tightly bind together the parts of the journal. The structure described constitutes a frame work upon which the plates forming the sides and enclosing members are mounted. Interposed between each adjacent pair of segmental sections 13 of each end member is a 30 perforated partition plate 31 of perforated

sheet metal; the edges of which are gripped between the flanged edges of the plates 32 with which each segment 13 is covered. Each plate 32 is turned over along its entire 5 perimetrical edge to provide flanges for this purpose and to overlap the entire peripheries of their enclosed segmental members 13. The outer edges of the partition plates 31 are extended beyond the periphery of the drum for cooperation with a door structure to be described and the inner edges of said plates extend beyond the corners of the journal members and are gripped between the inturned edges of per- 10 forated sheet metal plates 33 of which four are provided in the present instance having their ends gripped between the sides of the journal members and the segmental sections 13. The meeting faces of the sections forming the journal members are recessed to receive the edges of the plates 31 and 33, said inner edges of each series contributing to form inwardly directed flanges or deflecting members 34 for a purpose to be presently noted. The plates 33 are thus arranged to form a square axial channel in the center of the drum enclosing the shaft 27, the ends of which extend beyond the drum and are anchored in opposed walls of 15 the vat. The peripheral walls of the drum are formed by the provision of perforated sheet metal plates 35, the ends of which are secured to the flanges 19 of the segments 13 and are bent for attachment to the faces 17 to form the sides of the drum imparting a polygonal configuration thereto. 20 Each plate 35 is of a circumferential width to embrace only two faces 17 of each end segment exposing an opening into which articles are introduced, the door seat being provided by the aforesaid radial extension of the partition plates 31 and the out-turned longitudinal edges 36 of the said plates 35. A number of angle bars 37 are secured to the 25 face of the drum, one adjacent each of the said out-turned edges 36 to reinforce the drum structure and to provide a mounting for the door which consists of a rectangular frame 38 the sides of which are angular in cross section and are formed with a pair of apertured ears cooperating with similar ears 30 formed upon the ends of the angle bars, whereby the door frame may be swung toward or away from the door opening to respectively close or open the same, the opposed edges of the door structure abutting against and between the adjacent edges of the plate 31 and the edge 36. The door is manipulated through the medium of a handle 41 secured to enlargements 42 formed on one side of the door frame to dispose the handle at a convenient angle for grasping. The doors are held in closed position by means of a pair of locking devices each consisting of a bolt 43 slidably held in guiding 35 members 44 formed upon cross bars 45 connecting the longitudinal side members of the door frame. The locking bolts are urged toward locking position by means of springs 46 embracing the bolts and interposed between one of the guides 44 and a collar 47, one of which is affixed to each bolt, the bolts being held in openings provided in an adjacent pair of plate extensions 31 and 36. Each bolt 43 is formed with a lateral enlargement or lug 48 which is slidably held within the snugly receiving opening of one of the guides 44 when the bolts are in locking position. When the bolts are retracted sufficient to completely withdraw the lugs 48 40 from their recesses the bolts are given a quarter turn so as to throw the lugs out of alignment with the recesses and by engaging the faces of the guiding members 44 prevent return of the bolts to locking position. The door may now be freely opened or closed. When the door is closed and the bolts are to be shot it is but necessary to throw over the bent terminals thereof whereupon the springs 46 automatically reseat 45 the bolts. Each door frame is covered by means of a perforated plate 49 having outwardly turned flanges embracing the edges of the frame. 50 In the use of this type of machine the dyeing liquor, etc., is forced into the tubular shaft and issues from the perforations in sprays which are directed upon the articles contained in the drum during rotation of the latter so that the articles are uniformly 55 subjected to the action of the liquor, by this means and by submersion in the vat which is also filled with the liquor heated by live steam issuing from a perforated pipe 50 submerged at the bottom of the vat. In the present invention the liquor discharging from the tubular shaft enters first the square axial channel of the drum and passing through the perforated plates forming the sides thereof is distributed to the several 60 pockets into which the interior of the drum is divided. The distribution is enhanced by the presence of the flanges 34 which are directed radially into the axial channel and serve to deflect the sprays from one pocket 65 to the next during rotation of the drum, assuming the tubular shaft to be held stationary, although if desired the shaft may be fixed to the drum and the latter rotated by application of power initially to the 70 shaft. It will be seen that as the interior of the drum consists solely of plates in close contact at their edges and all having their contacting edges turned outwardly there is no opportunity for sharp projections of any 75 kind to extend into the drum and hence the articles cannot be injured or torn irrespective of the amount of tumbling to which they are subjected. It will be apparent that this construction of drum is also applicable 80

- to good advantage in the type of machine in which the liquor is not introduced into the center at all but relies solely upon submergence of the drum in the liquor for treatment of the articles. Owing to the presence of numerous outwardly projecting fins and flanges resulting from the construction described the liquor in the vat is constantly agitated during rotation of the drum.
- 10 Having thus described my invention, I claim:
1. An article container for dyeing machines or the like, comprising perforated plates assembled to form the container and having outwardly turned edges, a frame structure of separable parts applied to the exterior of the plates and means securing together the edges of the plates and parts of the frame to form a rigid structure.
  2. An article container for dyeing machines or the like, comprising perforate side plates, end plates having out-turned edges contacting with the end edges of the side plates to form the container and preserve a smooth interior, end frame members applied exteriorly to the end plates and seated within the edges of the latter and means for securing the frame members to the contacting edges of said side and end plates.
  3. An article container for dyeing machines, or the like, comprising a perforated peripheral wall, radial perforated partition plates therein, and frame members each comprising separable parts adapted to grasp therebetween the edges of said partition plates, and means for securing together the parts of the frame members and the plates thereto.
  4. An article container for dyeing machines or the like, comprising a perforated peripheral wall, and frame members having central openings, journal members fitted in said openings, and perforated plates extending through the container assembled to form a cavity and having their end edges grasped between the frame and journal members.
  5. An article container for dyeing machines or the like, comprising a peripheral wall, radial partitions defining pockets, an axial channel having perforated walls, and a perforated tubular supporting shaft extending through the channel and adapted to discharge thereinto.
  6. An article container for dyeing machines or the like, comprising a perforated cylinder, an axial channel therein quadrangular in cross-section and having perforated walls, and deflecting flanges extending radially into the channel from the corners thereof and seating in radial recesses in the channel end-walls.
  7. An article container, comprising a perforated peripheral wall and polygonal end walls, the latter comprising separable frame sections, and plates of sheet material corresponding in shape to the frame sections and secured thereto.
  8. An article container, comprising a perforated peripheral wall and polygonal end walls, the latter comprising separable frame sections, and plates of sheet material corresponding in shape to the frame sections having their edges bent outwardly and secured between the edges of the frame sections.
  9. In an article container, peripheral and end walls, an axial member composed of perforated plates having their edges joined and bent inwardly to form deflecting flanges, so and a perforated supporting axle extending through the axial member and mounted in the end walls.
  10. An article container, comprising a peripheral wall, end walls including end plates having their meeting edges bent outwardly, said plates having their end edges inserted between the said bent edges of the end plates, and an axial member formed of plates having their meeting edges bent toward the axis of the container and receiving between their said meeting edges the inner edges of the radial plates.
  11. In an article container, end members comprising segmental frame sections having inner spaced edges to define central openings, end plates having outwardly turned edges fitted between the frame sections, and substantially triangular journal members inserted within said openings and receiving said edges of the end plates between the journal members and the frame sections.
  12. In an article container, end members comprising separable segmental frame sections having inner spaced edges, defining inner journal openings, journal members fitted in said openings comprising substantially triangular separable sections, plates having bent edges inserted between the frame sections, and radial plates having their inner edges inserted between the sections of the journal members.
- In testimony whereof, I have hereunto signed my name at Philadelphia, Pennsylvania, this 10th day of August, 1922.
